UNITED STATES PATENT OFFICE.

ADOLPH F. MEYER, OF ST. PAUL, MINNESOTA.

RELAY MECHANISM.

Application filed December 2, 1927. Serial No. 237,240.

This invention relates to new and useful improvements in relay mechanisms, particularly of the hydraulic type, and is an improvement on the form shown in my pending 5 application, Serial No. 198,205, filed June 11, 1927.

An object of the present invention is to provide a hydraulic mechanism comprising a rotor or rotary member having a fluid conduit 10 pendently supported thereabove and having a connection with a fluid supply under pressure, and means being interposed between the rotor and the discharge end of the conduit for leading the fluid issuing from the conduit, to or away from the rotor, to control its rotation.

A further object of the invention is to provide a relay mechanism including a member mounted for rotation in either direction and 20 having a connection with other apparatus to be controlled thereby such as, for example, a valve adapted to control fluid pressure, and having a tube pendently mounted above the rotor with its discharge end positioned over 25 a pair of ducts, the lower ends of which are positioned adjacent to the rotor at opposite sides of its center, and a neutral passage being interposed between the ducts and also adapted to receive fluid from the tube and 30 functioning to lead fluid away from the rotor, and the tube having means for operatively connecting it with a physical-phenomena measuring device such as, for example, a watt 35 meter. The discharge end of the tube is preferably positioned so that, when the phenomenon is normal, it will discharge into the neutral passage, but when the phenomenon varies or changes either one way or the other from normal, the tube will be deflected by 40 such variation to direct a portion or all of the fluid into one or the other of the ducts, thereby causing the fluid passing through the ducts to impinge against the rotor and thus rotate it in either one direction or the other. 45 Motion of the hand of the device, measuring the phenomenon to be controlled, causes the tube to direct the discharging fluid into the neutral passage and said ducts, to control rotation of the rotor and therefore the operation 50 of the apparatus associated therewith.

A further object is to provide a hydraulic relay comprising a rotor having pockets or buckets provided on the periphery thereof, and also having a pair of divergent ducts arranged over the rotor and having their lower or discharge ends positioned adjacent to the

periphery of the rotor at each side of its center, and the upper ends of the ducts being connected and terminating below the discharge end of a pendently supported tube 60 having a connection with a supply of fluid, under pressure. A neutral passage is interposed between the ends of the ducts and is separated therefrom by walls having knife edges adapted to divide the stream of fluid 65 issuing from the tube, and the neutral passage is adapted to lead fluid away from the rotor so as not to cause rotation thereof.

A further object is to provide a relay of the class described, comprising a chamber 70 having a member mounted therein and adapted for rotation in either direction, the periphery of the member having a plurality of adjacently disposed peripheral pockets, separated by radial vanes or walls. Ducts are 75 arranged over the member for leading fluid against the periphery thereof, at either side of its center, to control rotation of the member in either direction, and a tube is mounted over the receiving ends of the ducts and has 80 its discharge end adapted for movement to direct all or a portion of the fluid into the ducts or into a neutral passage provided between the ducts, and the walls separating the ducts from the neutral passage having knife 85 edges adapted to divide or split the jet of fluid issuing from the tube, so that a small portion of the jet may be directed into one of the ducts to cause the member to rotate at a comparatively slow speed, and, if the 90 tube is deflected still farther in the same direction, a greater portion of the jet will be received in the duct, which will lead it against the rotatable member to increase its speed. Conversely, when the tube is deflected in the 95 opposite direction, fluid will be directed into the other duct, thereby causing the member to rotate in the opposite direction, and, when the tube is positioned directly over the neutral passage, substantially all of the fluid will 100 be received therein and lead away from the periphery of the member so as not to cause rotation thereof. The fluid discharged from the tube is delivered into the lower portion 105 of the chamber where it may be utilized to retard rotation of the member at high speeds as, for example, when the level of the fluid in the chamber is such as to immerse the lower portion of the member. In this case, the fluid will function as a brake or a drag on the member, when the latter tends to rotate at a high speed and, conversely, when the member

is rotating at a comparatively slow speed, little or no resistance will be offered to the member by the fluid in the chamber.

The particular object of the invention, therefore, is to provide an improved hydraulic relay mechanism adapted for use in connection with control mechanisms such, for example, as that set forth in my prior pending application, Serial No. 170,041, filed 10 February 21, 1927.

Other objects of the invention will appear from the following description and accompanying drawings and will be pointed out in the annexed claims.

15 In the accompanying drawings, there has been disclosed a structure designed to carry out the various objects of the invention, but it is to be understood that the invention is not confined to the exact features shown, as 20 various changes may be made within the scope of the claims which follow.

In the accompanying drawings forming part of this specification:

25 Figure 1 is a vertical sectional view on the line 1—1 of Figure 2, showing the rotor, the pendently supported tube, and the means provided for leading the fluid from the tube against the periphery of the rotor on either side of its center, for controlling its rotation.

30 Some of the parts are omitted in this figure; Figure 2 is a vertical sectional view on the line 2—2 of Figure 1;

Figure 3 is an enlarged detailed sectional view showing the tube positioned to direct 35 substantially all of the fluid into one of the ducts to rotate the rotor in a counter-clockwise direction;

Figure 4 is a sectional plan view on the line 4—4 of Figure 3;

40 Figure 5 is a sectional plan view on the lines 5—5 of Figures 2 and 3, showing the means for limiting movement of the tube;

Figure 6 is a view illustrating a conventional form of phenomenon measuring device;

45 Figure 7 is a view illustrating a modified form wherein the rotor is adapted for rotation in one direction only;

Figure 8 also illustrates another form of 50 the apparatus wherein the neutral passage is dispensed with, a member being interposed between the side delivery ducts for dividing or splitting the jet; and

55 Figure 9 is a view showing the jet-dividing member or "splitter", shown in Figure 8, removed from the apparatus.

In the selected embodiment of the invention here shown, for purposes of disclosure, there is illustrated an apparatus comprising 60 a casing 2 having a water chamber 3. A rotor 4, preferably having a plurality of adjacently disposed pockets 5 provided on the periphery thereof, is mounted within the casing 2, and is supported upon pivots 6 and 7, the latter being terminally provided

upon an adjusting screw 8, mounted in threaded engagement with the front wall of the casing and having a lock nut 9 for securing it in adjusted positions.

The rotor 4 preferably has an elongated hub 11, here shown as being integrally formed with the rotor. Upon the inner end of this hub is secured a pinion 12, meshing with a gear wheel 13 rotatably mounted upon a stud 14, secured to the rear wall 15 of the casing. 70 A pinion 16 is suitably secured to the gear 13 and meshes with another gear 17 mounted upon a reduced extension 18 of a shaft 19, mounted in a bearing 21 preferably provided in the rear wall 15, as shown in Figure 2. 75 The shaft 19 is adapted to be connected to the mechanism to be controlled, as will subsequently be described.

The gear wheel 17 is preferably frictionally secured to the extension 18 so as to permit 80 slippage of the gear upon the extension, in the event that the shaft 19 reaches the limit of its rotary movement in either direction, dependent, of course, upon the nature of the mechanism to which it is connected. The 85 means provided for thus frictionally securing the gear to the shaft 18 consist preferably in mounting upon the extension 18, leather or fiber washers 22 and 23, the former being interposed between the rear face of the hub 90 of the gear and a washer 24, and the latter being interposed between the front face of the gear and a washer 25. A compression spring 26 is interposed between the washer 25 and a similar washer 27, retained upon the extension 18 by a pin 28. The spring 26 constantly urges the washer 25, leather washers 22 and 23, and the gear wheel 17, rearwardly 95 against the metallic washer 24, seated against the shoulder 29 of the shaft 19. By thus mounting the gear 17 upon the shaft extension 18, it will be seen that the shaft 19 is 100 driven by friction.

A fluid conduit or tube 31 is pendently mounted above the rotor 4 with its discharge end spaced therefrom as shown in Figure 1. The tube has its upper end supported in a cylindrical extension 32, having a pipe 33 connected therewith which communicates 115 with the upper end of the tube through a flexible connection 34, as shown in Figure 2. The flexible connection 34 permits the lower end of the tube to be deflected by the slightest pressure or force. The lower end of the tube 31 is preferably guidingly supported in an arm 35, mounted for oscillatory movement upon vertical pivots 36 and 37, shown 120 in Figure 2. The swinging end of the arm 35 is interposed between a pair of adjusting screws 38, as shown in Figure 5, which function to limit the oscillatory movement of the arm. A tension spring 39 has one end connected with the tube 31 and its opposite end connected with an eye-bolt or screw 41, traversing the wall of the casing and having a 125 130

wing nut 42 received in threaded engagement therewith, whereby the tension of the spring 39 may be relatively adjusted to control the movement of the tube 31, in cooperation with 5 the phenomenon-measuring device.

The tube 31 is adapted to be deflected by a device such, for example, as a watt meter 43, having a connection 44 connecting the hand 45 thereof with the arm 35, as shown in Figures 1, 2, 3 and 6. When the tube 31 is thus operatively associated with the pointer 45 of the watt meter 43, it will be seen that when the hand 45 is moved by load variations in the apparatus connected with the watt meter, 10 the tube 31 will be deflected so as to discharge into one or the other of a pair of divergently disposed ducts 46 and 47, or into a neutral passage 48 provided between the ducts, as shown in Figures 1 and 3.

20 The ducts 46 and 47 are preferably curved, and have their lower ends positioned adjacent to the periphery of the rotor 4, and are preferably equally spaced from the vertical center of the rotor, as shown in Figures 1 and 25 3. However, when different speeds in clockwise and counter-clockwise rotation are desired, variable spacing may be used. The upper ends of the ducts preferably terminate in a receiving chamber 49, disposed directly 30 beneath the discharge end of the tube 31, as shown in Figures 1 and 3. The neutral passage 48 also communicates with the receiving chamber 49 and connects with ports 51 leading to the exterior of the curved wall 52, enclosing 35 the upper portion of the rotor 4. (See Figure 1).

In Figure 1, the tube 31 is shown positioned to direct substantially all of the fluid issuing therefrom into the neutral passage 48, whereby 40 the fluid will be led away from the rotor and onto the curved wall 52, from which it will flow into the lower chamber 3, as indicated by the arrows in Figure 1. In Figure 3, the tube is shown positioned to direct substantially 45 all of the fluid into the duct 46, thereby causing the issuing fluid to impinge against the radial walls or vanes 53, separating the peripheral pockets 5 in the rotor 4. Such impinging of the water against the 50 walls 5 will cause the rotor to rotate counter-clockwise, as indicated by the arrow in Figure 3. When the tube is deflected to the dotted line position shown in Figure 3, the fluid will be directed into the duct 47 which will cause 55 the rotor 4 to rotate clockwise. Thus, it will be seen that deflection of the tube 31 will control rotation of the rotor. The walls separating the ducts 46 and 47 from the neutral passage 48 are provided with knife edges 60 50 which function to divide the jet of water discharging from the conduit or tube 31.

The neutral passage 48 may be made as narrow as desired in relation to the size of the jet issuing from the tube, depending upon 65 the sensitiveness desired. The narrower the

neutral passage, the more responsive will be the relay mechanism to variations and changes in the phenomenon. This feature determines what, in practice, is known as the "dead zone."

In order to afford a clearer explanation of the operation of this novel relay mechanism, I have shown in Figure 2, the mechanism operatively connected with a form of pilot valve 54, functioning to control fluid pressure in a pipe line 55 or other apparatus, not shown. A valve 54 operates between two valve seats 56 and 57 and has a stem 58 movably supported in a guide 59, suitably secured to the base 61. A water chamber 62 is shown 70 beneath the valve seat 57 and is connected by a pipe 63 to the discharge side of the pump 64, the intake side of which is connected by a pipe 65 to the chamber 3 beneath the rotor. The pump 64 delivers fluid under pressure to 75 the tube 31, through a pipe 66 connecting the water chamber 62 with the pipe 33. Means, not shown, are provided for constantly operating the pump 64. The fluid circulating through the chamber 62 will therefore be 80 under pressure, which pressure acts against the lower end of the valve 54 and tends to move it upwardly into engagement with the valve seat 56. Upward movement of the valve 85 54 is resisted by fluid pressure in a chamber 67, here shown as defined by diaphragms 68 and 69 and an annular member 71. A flanged stud 72 has its lower end engaging the upper end of the valve stem 58 and has one end of a tension spring 73 connected with its upper 90 end. The other end of the spring is connected to a threaded stem 74, adapted for vertical movement by such means as a bevel gear 75, received in threaded engagement with the stem 74 and meshing with a pinion 76, secured to the operating shaft 19 of the relay mechanism. A pipe 77 connects the pressure chamber 67 with a smaller pressure chamber 78, provided between the valve seats 56 and 57 95 as shown. The chamber 79, shown above the pressure chamber 78 is preferably connected with the water chamber 3, provided in the lower portion of the casing 2.

Whenever the rotor 4 turns in a clockwise direction, it causes the bevel gear 75 to turn 100 clockwise and thus increase the tension in the spring 75, providing the rod 74 is threaded right hand, as shown. An increase in spring tension results in an upward movement of the member 72 and the pilot valve 54 with a 105 consequent increase in the inlet seat opening 57 and a reduction in the outlet seat opening 56. This will result in an increase in fluid pressure in the chamber 78, the pipes 55 and 77, and the chamber 67, sufficient so 110 that the downward fluid pressure on the enlarged area of disk and diaphragm 69, over that on disk and diaphragm 68, will substantially balance the tension of the spring 73.

The fluid pressure in the pipe 55, or the mo- 115

tion of the shaft 19, may be utilized in any desired manner to control the apparatus connected with the watt meter.

Figure 7 illustrates a modified form where-
5 in the rotor 4 is adapted for rotation in one direction only. As here shown, the duct 81, corresponding to the duct 47 in Figures 1 and 3, has its lower end connected with the discharge end of the duct 46, so that fluid dis-
10 charged thereinto will be led against the periphery of the rotor at substantially the same point as the fluid passing through the duct 46, thereby causing the rotor to rotate in one direction or counter-clockwise, when
15 viewed as shown in Figure 7. A neutral passage 82 is provided between the ducts 46 and 81 to lead the fluid away from the rotor. The function of this passage is similar to the function of the passage 48, shown and described
20 with reference to the previous figures. The ducts 46 and 81 in Figure 7 are separated from the neutral passage 82 by walls 83, each having a knife edge 84 adapted to divide the jet of fluid issuing from the tube.

25 In the particular form of structure here disclosed, a small variation in phenomenon directing a small portion of the fluid issuing from the tube to the rotor through one of the ducts, will cause a gradual accumulation
30 of fluid in the pockets of the rotor until its weight is sufficient to cause rotation. The resulting rotation will usually be intermit-
35 tent. A relatively large variation in the phenomenon directing a relatively large portion of the fluid issuing from the tube into one of the ducts, will cause rapid rotation of the rotor through the combined dynamic pres-
40 sure of that portion of the issuing jet deflect-
ed against the walls or vanes 53 on the periph-
ery of the rotor, and the weight of the fluid accumulating in the pockets thereof.

45 When the means interposed between the tube and the rotary member are arranged as shown in Figure 7, the member will rotate in only one direction. The rate of rotation will depend upon the amount the tube is deflected to either side of the neutral passage. If the neutral passage is made wide in relation to the width of the issuing jet, then the member will tend to remain stationary, for small variations of the phenomenon from normal. On the other hand, if the neutral passage is made narrower than the jet, then
50 some fluid will continually be led to the rotor to cause slow rotation, even when the phenomenon is normal. In both cases a large variation of the phenomenon from normal in either direction will cause relatively rapid rotation of the rotor.

55 60 Under some conditions it may be found desirable to eliminate the "dead zone" altogether. This can readily be accomplished, as shown in Figure 8, by inserting in the neutral passage 48, a jet-dividing member
65 85, which I shall hereinafter refer to as a

"splitter". (See Figure 9.) This splitter is inserted into the neutral passage 48, and is suitably secured therein. The opposed upper walls of the splitter are tapered inwardly and terminate in a knife edge 86, positioned
70 in alignment with the axis of the rotor 4 and the imaginary pivotal point of the tube 31. When the phenomenon is normal, the knife edge 86 will divide the issuing jet into two equal portions, which will flow through
75 their respective ducts 46 and 47 to the rotor. When the issuing jet is thus equally divided between the two ducts, the rotor will come to rest. This results because one jet portion tends to rotate the rotor in one direction while the other tends equally to rotate the rotor in the opposite direction. The slight-
80 est variation of the phenomenon from normal, however, will immediately cause a relatively greater portion of the issuing jet to be
85 discharged to one side of the knife edge 86 of the splitter 85, resulting in relatively rap-
id rotation of the rotor, and consequently a rapid readjustment of the associated mech-
anism.

90 I claim as my invention:

1. In a relay mechanism, the combination with a main device actuatable responsively to variations and changes in a phenomenon, of a rotary element, a fluid conduit supported above said element, and an operative connection between said conduit and said main device for moving the conduit responsively to said variations and changes so as to direct the discharging fluid to the rotary element 100 in such a manner as to control rotation of the rotor in either direction.

2. In a relay mechanism, the combination with a main device actuatable responsively to variations and changes in a phenomenon, of a rotary element, a fluid conduit supported above said element, means interposed between said element and said conduit adapted to lead fluid discharging from the conduit to the element, and an operative connection between the conduit and the main device for moving the discharge end of the conduit responsively to said variations and changes so as to direct the discharging fluid to said rotary element in such a manner as to control rotation of the member in either direction.

3. In a relay mechanism, the combination with a main device actuatable responsively to variations and changes in a phenomenon, of a rotary element, a fluid conduit supported above the element, means interposed between the element and the conduit for leading the fluid discharging from the conduit against and away from the rotary element and an operative connection between the conduit and the main device for moving the discharge end of the conduit responsively to said variations and changes so as to direct substantially all or a portion of the dis-

charging fluid against or away from the element, to control its rotation.

4. In a relay mechanism, the combination with a main device actuatable responsively to variations and changes in a phenomenon, of a rotary element, a fluid conduit supported above the element, ducts interposed between the element and the conduit for leading fluid discharging from the conduit to the element to rotate it, a passage for leading the discharging fluid away from the element, and an operative connection between the conduit and the main device for moving the discharge end of the conduit responsively to said variations and changes so as to direct substantially all or a portion of the discharging fluid against or away from the element, to control its rotation.

5. In a relay mechanism, the combination of a rotary element, a tube pendently supported above the rotary element and having a connection with a fluid supply, a duct adapted to receive fluid from the tube and leading to one side of the center of the rotary element, a neutral passage adjacent to said duct for receiving fluid from the tube and leading it away from the rotary element, and means for deflecting said tube.

6. In a relay mechanism, the combination with a main device actuatable responsively to variations and changes in a phenomenon, of a rotor adapted for movement in either direction, a fluid conduit supported above the rotor, means for leading fluid discharging from the conduit against the rotor, a passage for leading discharging fluid away from the rotor, and an operative connection between the conduit and the main device adapted responsively to said variations and changes to move the conduit so as to direct a portion or all of the fluid against the rotor, to control its rotation.

7. In a relay mechanism, the combination of a rotor, a tube pendently supported over the rotor and having its discharge end spaced from the periphery thereof, divergent ducts interposed between the periphery of the rotor and the discharge end of the tube adapted to receive fluid issuing from the tube and to direct it against the periphery of the rotor, a neutral passage arranged between the ducts and also adapted to receive fluid discharging from the tube to lead it away from the rotor, and means for deflecting the tube to direct the fluid issuing therefrom into the ducts and passage, to control rotation of said rotor.

8. In a relay mechanism, the combination of a rotor adapted for movement in either direction, a fluid conduit supported above the rotor, ducts for directing fluid discharging from the conduit against the rotor, at either side of its center, to rotate the rotor in either direction, a neutral passage between said ducts for leading the fluid away from the ro-

tor, and means operable to deflect the conduit so as to direct a portion or all of the fluid discharging therefrom into said ducts and said passage, to control rotation of the rotor in either direction.

9. In a relay mechanism, the combination of a rotor adapted for movement in either direction, a fluid conduit supported above the rotor, a pair of divergent ducts arranged between the rotor and the discharge end of the conduit for leading discharging fluid against the periphery of the rotor, at either side of its center, to rotate the same in either direction, a neutral passage between the ducts for leading the fluid away from the rotor, walls separating the ducts from the neutral passage, each wall having a knife edge adapted to divide the stream issuing from the conduit, and means operable to deflect the conduit so as to direct the fluid discharging therefrom into said ducts and said passage, to control rotation of the rotor in either direction.

10. In a relay mechanism, the combination of a rotor having peripheral pockets, a fluid conduit supported above the rotor, ducts having their lower ends terminating adjacent to the periphery of the rotor at opposite sides of its center and having their upper ends positioned to receive fluid issuing from the conduit, a neutral passage between said ducts for directing the fluid away from the rotor, and means operable to cause a portion or all of the fluid issuing from the conduit, to be directed into one or the other of the ducts and into the neutral passage, to control rotation of the rotor.

11. In a relay mechanism, the combination of a rotor having peripheral pockets, a fluid conduit supported above the rotor, ducts interposed between the periphery of the rotor and the discharge end of the conduit for leading fluid discharging therefrom into the pockets of the rotor, at either side of its center, a neutral passage between the ducts for leading fluid away from the rotor, knife-edged walls separating the ducts from the neutral passage, and means operable to deflect the conduit so as to direct fluid issuing therefrom into the ducts and neutral passage in such a manner as to control rotation of the rotor in either direction.

12. In a relay mechanism, the combination of a casing having a water chamber in the lower portion thereof, a rotor mounted in the casing and having the lower portion of its periphery immersed in the water chamber, a tube pendently supported over the rotor, and means for leading the fluid issuing from the tube to the periphery of the rotor to control its rotation.

In witness whereof, I have hereunto set my hand this 23rd day of November, 1927.

ADOLPH F. MEYER.
